UNITED STATES PATENT OFFICE.

LEE STURGES, OF CHICAGO, ILLINOIS.

FRAME FOR BICYCLES, &c.

SPECIFICATION forming part of Letters Patent No. 614,905, dated November 29, 1898.

Application filed July 15, 1897. Serial No. 644,662. (No model.)

To all whom it may concern:

Be it known that I, LEE STURGES, a citizen of the United States, residing at Chicago, in the county of Cook and State of Illinois, have 5 invented certain new and useful Improvements in Frames for Bicycles and other Machines, of which the following is a specification.

The invention consists in the features of 10 novelty which are hereinafter fully described with reference to the accompanying drawings, which are made a part hereof, and in which—

Figure 1 is a side elevation of a portion of 15 the frame of a bicycle embodying the invention in its preferred form. Fig. 2 is a section thereof on the line 2 2, Fig. 1. Fig. 3 is a transverse section thereof on the line 3 3, Fig. 2. Fig. 4 is a longitudinal section of 20 the inner sleeve which enters into the construction of the cross-head. Fig. 5 is a plan view of the two parts of which the cross-head and stubs are formed. Fig. 6 is an inner face 25 view of one of said parts. Fig. 7 is a diagram showing approximately the shape of the blank from which the part shown in Fig. 6 may be made.

The foregoing figures show the construction 30 of the parts when the fork-arms are joined to the stub through the medium of a single stem.

A represents the lower reach, B the king-post, and C the stem by which the rear fork-arms are connected with the cross-head D. 35 This cross-head in the preferred form of the invention is made up of two parts E E' and a sleeve F. The part E comprises a tubular portion e, which is without any longitudinal seam or division, one-half e¹ of the stub for 40 receiving the reach A, one-half e² of the stub for receiving the king-post B, and one-half e³ of the stub through the medium of which the fork-arms are connected with the cross-head. The part E' comprises similar portions, excepting that they are in reverse, so 45 that when the two parts E and E' are brought together the several halves of stubs similarly lettered will unite, thereby completing the stubs for the reach, the king-post and the

fork-stem. The peculiarity of this construction is that when the parts are assembled the cross-head will have a transverse seam and no longitudinal seam, while all of the stubs will have longitudinal seams, all of which lie in a single plane, which in the illustration given is strictly perpendicular to the axis of the cross-head; but mathematical accuracy in this respect is not an essential feature of the invention, and any formation of the parts E and E' which will avoid a longitudinal seam 55 of the cross-head and seams of the stubs which lie in planes that are longitudinal with respect to the cross-head is within the scope of the invention.

The tube or sleeve F is disposed within 60 the tubular portions e e, and its extremities are spun over, as shown at f, for the purpose of more firmly maintaining the proper relative positions of the parts E E', and by preference the tube is provided on its interior 65 with spun beads f', for limiting the insertion of the cups.

The rear fork-arms G are both made of a single piece of tubing, which is bent at its middle to a practically semicircular shape, so 70 as to provide a curved crown, as shown at g. This crown fits in a socket of corresponding shape in a crown-piece H, having a stem h, which telescopes with the stub e³ of the cross-head. This crown-piece is made up of two 75 parts which are of similar shape, each of which parts comprises one-half of the crown-piece and one-half of the stem, the seam being in a plane which cuts both of the fork-arms centrally. It will be seen more clearly 80 upon reference to Fig. 3 that the parts of which the fork-stem, considered as a whole, are made break joints with each other—that is to say, in the illustration given the seams of the stub e³ and stem h lie in planes which are 85 perpendicular to each other. Preferably also 90 these parts are so shaped that the fork-stem is of elliptical cross-section, with its longest diameter horizontal.

Having thus described my invention, the 95 following is what I claim as new therein and desire to secure by Letters Patent:

A frame for bicycles, having a cross-head

and a stub proceeding rearward from it, said cross-head and stub being formed of two parts so shaped that the seams of the stub will lie in a plane which is transverse to the cross-head, and a fork having a crown-piece provided with a stem which telescopes with the stub of the cross-head, said crown-piece and

its stem being formed of two parts so shaped that the seams of the stem and the stub will break joints, substantially as set forth.

LEE STURGES.
